(57) **CLAIM**

The ornamental design for a baby carrier, substantially as shown and described.

DESCRIPTION

FIG. 1 is a top, perspective view of the baby carrier, the view showing my new design;

FIG. 2 is a front elevation view thereof;

FIG. 3 is a rear elevation view thereof;

FIG. 4 is a side view thereof;

FIG. 5 is a side view thereof;

FIG. 6 is a top view thereof;

FIG. 7 is a bottom view thereof; and,

FIG. 8 is a bottom, perspective view thereof.

The broken lines in the drawings show portions of the baby carrier that form no part of the claimed design.
